JOHN F. HALSTEAD, OF BROOKLYN, NEW YORK, ASSIGNOR TO INTERNATIONAL CIGAR
MACHINERY COMPANY, A CORPORATION OF NEW JERSEY

STOGIE HEADING DEVICE

Application filed January 18, 1930. Serial No. 421,699.

This invention relates to cigars of the slender type having a tail at their head end known as stogies, and particularly to a device and method for heading the same.

5 The main object of the present invention is to provide for the production of stogies by machine. To this end it is an object of the invention to produce an improved stogie cigar adapted to machine manufacture. To 10 the same end it is another object of the invention to provide an improved method of stogie manufacture. Still another object of the invention is to provide mechanism capable of substitution or attachment to existing cigar machines to form a device for 15 heading stogies. In furtherance of the above it is an object of the invention to provide a method and mechanism for producing the characteristic tails of stogie cigars. With 20 these and other objects not specifically mentioned the invention consists in certain constructions and combinations hereinafter described and then specifically set forth in the claims hereunto appended.

25 In the accompanying drawing, which forms a part of this specification and in which like characters of reference indicate the same or like parts, Fig. 1 is a side view of the improved stogie cigar; Fig. 2 is a side view in 30 cross section of the head end of a stogie made in accordance with the invention; Fig. 3 is a plan view of a stogie heading device constructed in accordance with the invention. Fig. 4 is an end elevation of the device 35 shown in Fig. 3; Fig. 5 is a side elevation of a positioning device for positioning the stogie. Fig. 6 is a sectional end elevation taken on line 6—6 of Fig. 5.

A cigar of the stogie type made in accordance with the invention comprises a 40 filler, a binder enclosing and projecting beyond the head end of the filler and a wrapper enclosing said filler and said binder and projecting beyond the latter in order to provide the material for the tail of the stogie. The method employed in carrying the invention into effect consists in enclosing the 45 filler within a binder projecting beyond the head end of the filler to form a bunch and 50 winding a wrapper about the bunch to the head end of the filler and about the binder beyond said end and on itself beyond the binder, to thereby form a tail at the head end.

In carrying the invention into effect there 55 is also provided mechanism, comprising means for rotating a stogie bunch having a binder projecting beyond the head end of its filler and a wrapper projecting beyond the binder, means for supporting the head 60 end of the bunch and its projecting binder and wrapper, and means coacting with said supporting means when said rotating means is in action to roll the wrapper over the head 65 end of the bunch and on the binder beyond said bunch and on itself beyond the binder.

The various means referred to may be varied widely in construction within the scope of the claims, for the particular device selected to illustrate the invention is but one of 70 many possible concrete embodiments of the same. The invention therefore is not to be restricted to the precise details of the structure shown and described.

Referring now to the drawing, as shown 75 in Figs. 1 and 2, the new stogie is provided with a filler F, of the desired long slender shape and this filler is enclosed in a binder B projecting a distance beyond the head end 80 of the filler to provide projection P thereby forming the stogie bunch. This bunch may be made and transferred or handled in the same way that the ordinary bunch is the only difference being that the transfer arm which carries the binder from the binder 85 cutter to the rolling apron of the ordinary bunch making machine, is so positioned as to place the end of the binder the length of the projection P beyond the head end of the filler charge to form said projection and 90 of course the means for trimming the head end of the bunch is omitted. The wrapper W, encloses the bunch as shown in Fig. 2 this wrapper being wound on the body of 95 the bunch in the manner ordinarily employed in wrapping cigars. The wrapper therefore is placed to project beyond the head end of the filler and is wound about the bunch to the head end of the filler thereof and about 100 the binder beyond the end of the filler and

then on itself beyond the bunch to form the characteristic tail T of the stogie.

To apply the wrapper to the head end of the stogie the ordinary wrapper applying mechanism of the conventional cigar machine is modified as shown in Figs. 3 and 4. A stationary concave open sided heading block 10 is provided extending along and beyond the head end of the bunch for supporting the head end of the bunch and also its projecting binder and wrapper. Cooperating with the block to engage the wrapper at the open side of said block is a roller 11 set at an angle to fit the taper of the stogie head 15 and having a tapered portion extending axially of the stogie to wind the tail T. This roller is supported in an adjustable fork 12 on the cam operated arm 13 on which it is mounted in lieu of the flag roller used on ordinary cigar machines. The roller 11 is rotated by the rotating bunch which is supported and rotated by the usual rollers 14 which are similar to those used in conventional cigar machines except that in practice they are rotated somewhat faster in order to completely wrap the long slender stogie bunch and its tail without increasing the time required. Owing to the longer taper of the stogie head no "flag" is required such as that usually found in machine made cigars and the flag cutter is accordingly eliminated and the flag roller replaced by the head and tail roller above described.

In order that the stogie head may be accurately positioned without injury to the tail while its tuck end is being trimmed, an operation ordinarily performed in the reroller of the conventional cigar machine, a positioning ring 15 is provided having a large enough bore to pass over the head end of the stogie some distance back of the tail, this ring being suitably supported by horizontal arms 16 attached to the ring close to its circumference to provide plenty of clearance for the tail. This locating ring takes the place of the conventional head-knurler used in the ordinary cigar machines. It will be noted that the improved stogie unlike hand made cigars which have a filler and wrapper only, is provided with both a bunch binder and wrapper both of which cooperate in forming the tail. The binder also serves to hold the filler charge together while being transferred and otherwise acted on by the units of the cigar machine. The additional cost of the binder is however compensated for by the saving in expensive wrapper material and other economies of machine manufacture.

In view of the foregoing, further detailed description of the operating device is deemed unnecessary and is therefore omitted in the interest of brevity.

What is claimed is:

1. A stogie heading device for cigar ma-

chines, comprising means for rotating a stogie bunch having a binder projecting beyond the head end of its filler and a wrapper projecting beyond the binder, means for supporting the head end of the bunch and its projecting binder and wrapper, and means coacting with said supporting means when said rotating means is in action to roll the wrapper over the head end of the bunch and on the binder beyond said end and on itself beyond the binder. 70 75

2. A stogie heading device for cigar machines, comprising means for rotating a stogie bunch having a binder projecting beyond the head end of its filler and a wrapper projecting beyond the binder, means for supporting the head end of the bunch and its projecting binder and wrapper, and means coacting with said supporting means when said rotating means is in action to roll the wrapper over the head end of the bunch and on the binder beyond said end and on itself beyond the binder, said rotating means including a gang of rollers engaging the major portion of the bunch. 80 85 90

3. A stogie heading device for cigar machines, comprising means for rotating a stogie bunch having a binder projecting beyond the head end of its filler and a wrapper projecting beyond the binder, means for supporting the head end of the bunch and its projecting binder and wrapper, and means coacting with said supporting means when said rotating means is in action to roll the wrapper over the head end of the bunch and on the binder beyond said end and on itself beyond the binder, said supporting means including a concaved open-sided heading block extending along and beyond the head end of the bunch. 95 100 105

4. A stogie heading device for cigar machines, comprising means for rotating a stogie bunch having a binder projecting beyond the head end of its filler and a wrapper projecting beyond the binder, means for supporting the head end of the bunch and its projecting binder and wrapper, and means coacting with said supporting means when said rotating means is in action to roll the wrapper over the head end of the bunch and on the binder beyond said end and on itself beyond the binder, said rolling means including a roller engaging the wrapper and rotated by the rotating bunch. 110 115 120

5. A stogie heading device for cigar machines, comprising means for rotating a stogie bunch having a binder projecting beyond the head end of its filler and a wrapper projecting beyond the binder, means for supporting the head end of the bunch and its projecting binder and wrapper, and means coacting with said supporting means when said rotating means is in action to roll the wrapper over the head end of the bunch and on the binder beyond said end and on itself 125 130 135

beyond the binder, said supporting means including a concaved opensided heading block extending along and beyond the head end of the bunch, and said rolling means including
5 a roller engaging the wrapper at the open side of said block and rotated by the rotating bunch.

In testimony whereof, I have signed my name to this specification.

10 JOHN F. HALSTEAD.
